BAKEWARE DISPLAY RACK OR SIMILAR ARTICLE

Elmer L. Reibold, Park Ridge, William W. Timpe,
Prospect Heights, and Spartaco Trivellini, Roselle, Ill.,
assignors to Market Masters, Inc., Elk Grove Village,
Ill., a corporation of Illinois

Filed July 22, 1969, Ser. No. 18,308

Term of patent 14 years

Int. Cl. D6—01

U.S. Cl. D80—10

FIG.1

FIG.2

FIG. 4

FIG. 5

FIG. 6

FIG.7

FIG.9

FIG.8

FIG. 11

FIG. 10

FIG.12

FIG. 1 is a perspective view of a bakeware display rack embodying our new design;

FIG. 2 is a front elevational view thereof;

FIG. 3 is a top plan view thereof;

FIG. 4 is a rear elevational view thereof;

FIG. 5 is a side elevational view thereof;

FIG. 6 is an elevational view of the opposite side thereof, the broken line representations of bakeware being for purposes of illustration only;

FIG. 7 is a perspective view of an additional embodiment of a bakeware display rack embodying our new design;

FIG. 8 is a front elevational view of the embodiment of FIG. 7;

FIG. 9 is a top plan view of the embodiment of FIG. 7;

FIG. 10 is a rear elevational view of the embodiment of FIG. 7;

FIG. 11 is a side elevational view of the embodiment of FIG. 7; and

FIG. 12 is an elevational view of the opposite side of the embodiment of FIG. 7, the broken line representations of bakeware being for purposes of illustration only.

We claim:

The ornamental design for a bakeware display rack or similar article, substantially as shown and described.
